Vincent Paul Bourne-Vanneck, New York, N. Y.

Application October 10, 1952, Serial No. 21,794

Term of patent 14 years

(Cl. D81—26)

To all whom it may concern:

Be it known, that I, Vincent Paul Bourne-Vanneck, a British subject residing in the city of New York, in the county of New York and the State of New York, have invented a new, original, and ornamental Design for a Flame Pad or Similar Article, of which the following is a specification, reference being had to the accompanying drawing, forming a part hereof.

Figure 1 is a top-plan view of a flame pad, or similar article, showing my new design;

Figure 2 is a side elevational view thereof;

Figure 3 is a bottom-plan view thereof; and

Figure 4 is a cross-sectional view taken on the line 4—4 in Figure 1.

I claim:

The ornamental design for a flame pad or similar article, as shown.

VINCENT PAUL BOURNE-VANNECK.
